(57) CLAIM

I claim the ornamental design for the portion of a handle for a nail care instrument, as shown and described.

DESCRIPTION

FIG. 1 is a perspective view of the portion of a handle for a nail care instrument of the subject invention;

FIG. 2 is a right side view of the portion of a handle of FIG. 1;

FIG. 3 is a top view of the portion of a handle of FIG. 1;

FIG. 4 is a left side view of the portion of a handle of FIG. 1;

FIG. 5 is a bottom view of the portion of a handle of FIG. 1;

FIG. 6 is a front end view of the portion of a handle of FIG. 1; and,

FIG. 7 is a rear end view of the portion of a handle of FIG. 1.

Details shown in broken lines are for illustrative purposes only, and form no part of the claimed design.
